UNITED STATES PATENT OFFICE.

WILLIAM J. REYNOLDS, OF NICHOLASVILLE, KENTUCKY, ASSIGNOR OF ONE-FOURTH
TO WILLIAM BROWN BUFORD, OF NICHOLASVILLE, KENTUCKY.

HEMP-BRAKE.

1,331,526.

Specification of Letters Patent. Patented Feb. 24, 1920.

Application filed January 23, 1919. Serial No. 272,756.

To all whom it may concern:

Be it known that I, WILLIAM J. REYNOLDS, a citizen of the United States, residing at Nicholasville, in the county of Jessamine and State of Kentucky, have invented new and useful Improvements in Hemp-Brakes, of which the following is a specification.

This invention relates to hemp brakes having a rotatable beater, and its object is to provide a simple and highly efficient machine of this kind, and also one which is rapid in operation.

The object stated is attained by means of a novel combination and arrangement of parts to be hereinafter described and claimed, and in order that the same may be better understood, reference is had to the accompanying drawings forming a part of this specification.

In the drawings,

Figure 1 is an elevation of the machine;

Fig. 2 is a longitudinal section thereof;

Fig. 3 is a cross-section, and

Fig. 4 is a plan view with parts in section.

Referring specifically to the drawings 10 denotes a disk which is fast on a shaft 11 journaled in bearings 12 supported on laterally spaced rails 13 at the top of a supporting frame consisting of standards 14 rising from suitable base rails 15. The shaft 11 is equipped with a pulley 16 belted to a suitable power source, whereby the shaft is 35 driven to rotate the disk 10. Any other suitable means for driving the shaft 11 may be provided.

The disk 10 is armed on both sides with beater bars 17, which latter may be of angle iron bolted or otherwise rigidly fastened to the disk. These bars are not set radially on the disk, but they are arranged tangentially with respect to a circle having for its center the center of the shaft 11.

45 The disk 10 is also armed with wings 18 extending radially from its periphery, and having a function to be presently described.

The upper half of the disk 10 is housed in a hood 19 having feed openings 20 on one side of the shaft 11, there being an opening in each side of the hood so that the stalks may be fed to both sides of the disk 10, to be acted on by the beater bar 17 thereon. The machine therefore has a large capacity

and a large output within a limited period 55 of time is rendered possible.

The hood 19 has bottom recesses 21 to clear the shaft 11, and it seats between the rails 13, and is removably supported on cross bars 22 connecting said rails adjacent to 60 their ends.

The lower half of the disk 10 is not housed and works close to a floor 23 seating on the base rails 15 between the stands 14.

65 On each side of the floor 23 is hinged, as shown at 24 a guard plate 25 to prevent the hurds from being scattered over the operators. The hurds knocked off the stalks are carried along the floor 23 by the wings 18 70 and discharged from the forward end thereof, and the hurds which escape sidewise from the disk 10 are caught by the plates 25 and may be thrown back onto the floor by swinging the plates upwardly as shown in 75 Fig. 3.

The feed openings 20 extend down to the rails 13, and the latter support feed tables 26 leading to said openings. The outer ends 80 of the feed tables are supported by legs 27.

In operation, the stalks are laid on the tables 26 and fed to each side of the disk 10 through the feed openings 20, one operator being required for each side of the machine. Each operator places a bunch of stalks on 85 his feed table and pushes the stalks through the feed opening against the side of the disk, so that they may be acted on by the beater bars 17. The hurds are disposed of by the radial wings 18 as hereinbefore described. 90 After one end of the bunch of stalks has been operated on, the bunch is reversed and the other end is inserted and subjected to a beating action by the bars 17.

In practice, the machine may be mounted 95 on a truck for convenience in transportation to and from the place of use.

I claim:

1. A hemp brake comprising a rotary disk, beater bars mounted on the side of the disk 100 and extending in the direction of the periphery thereof, a support for feeding the stalks endwise to the side of the disk carrying the beater bars, and radial hurd-discharging wings mounted on the periphery of 105 the disk and extending transversely thereof.

2. A hemp brake comprising a rotary disk, beater bars mounted on the side of the

- disk and extending in the direction of the periphery thereof, a support for feeding the stalks endwise to the side of the disk carrying the beater bars, radial hurd-discharging wings mounted on the periphery of the disk, and a guard plate alongside the disk and adjustable to carry the hurds back to the disk for discharge by the radial wings.
- 5 3. A hemp brake comprising a rotary

disk, beater bars mounted on the side of the 10 disk and extending in the direction of the periphery thereof, a support for feeding the stalks endwise to the side of the disk carrying the beater bars, and means on the disk for discharging the hurds.

15

In testimony whereof I affix my signature.

WILLIAM J. REYNOLDS.
